(57) **CLAIM**

The ornamental design for a potentiometer, as shown and described.

DESCRIPTION

1. Potentiometer
- 1.1 is a perspective view;
- 1.2 is a front view;
- 1.3 is a rear view;
- 1.4 is a side view;
- 1.5 is a side view;
- 1.6 is a top view; and
- 1.7 is a bottom view.

A closed circuit variable resistance potentiometer with male audio style jack for the patchable attenuation of audio signals and electrical voltage signals; the dashed lines the circumscribe the center of the Jack are environmental only and are not part of the claimed design.

1 Claim, 7 Drawing Sheets
